UNITED STATES PATENT OFFICE.

HENRY C. BLACK, OF OAKLAND, CALIFORNIA.

CAN-END-SOLDERING MACHINE.

SPECIFICATION forming part of Letters Patent No. 700,890, dated May 27, 1902.

Application filed June 14, 1901. Serial No. 64,547. (No model.)

To all whom it may concern:

Be it known that I, HENRY C. BLACK, a citizen of the United States, residing at Oakland, county of Alameda, State of California, have 5 invented certain new and useful Improvements in Can-End-Soldering Machines; and I do hereby declare the following to be a full, clear, and exact description of the same.

The present invention relates to a bath-solderer designed for use in connection with soldering of tops and bottoms onto can-bodies; and the object of the invention is to reduce the amount of solder at present used in the soldering of the tops and bottoms onto 15 can-bodies, thereby reducing the cost of the cans per thousand.

In order to comprehend the invention, reference should be had to the accompanying sheet of drawings, wherein—

20 Figure 1 is a broken side view of the machine, with the primary heater and fluxing-receptacle connected therewith. Fig. 2 is a top plan view of the mechanism illustrated in Fig. 1 of the drawings, the endless carrier 25 for the cans being removed. Fig. 3 is a rear end view in elevation. Fig. 4 is a horizontal sectional top plan view taken on line xx of Fig. 3 of the drawings; Fig. 5, a front view in elevation, partly broken away; and Fig. 6 30 is a cross-sectional view on line yy , Fig. 2, disclosing the arrangement of the flux-baths.

The letter A is used to indicate one of the supporting-frames for the solder-bath receptacles, and A' one of the supporting-frames 35 for the primary heater, these frames being united by the flux-holding troughs D and cross-bars d^x .

Within frame A is supported the soldering-bath receptacles B B', which are arranged 40 parallel and each provided with a longitudinal slot a . These receptacles are held within the heat-retaining shells B² B³. Each shell is formed with a longitudinal opening a' in its upper surface, through which projects the 45 slotted extension b of the solder-bath receptacles. In the present case the solder-bath receptacles consist of tubes having their ends closed by screw-plugs b' . Below the heat-retaining shells a series of burners C are arranged, the jet end of each burner extending 50 within the shells B² B³ through openings

b^2 in the under face of said shells. These burners are connected to the air and gas supply pipes C' C² by branch pipes d .

To the forward end of frame A is attached 55 one end of the flux-holding troughs D, which are arranged parallel and in line with the heat-retaining shells. The opposite ends of the troughs are connected to frame A', which supports the primary can-heater. This heater 60 consists of a suitable trough D', filled with any suitable non-absorbent material of heat, as asbestos. The trough in width is less than the length of the can D², so that when the same rests thereon the top f and bottom f' 65 will extend beyond the sides of said trough. Below this trough a series of burners D³ are arranged, the flame from which bears against the under surface of the trough in order that the heat may be deflected to each side thereof. 70 These burners are connected to the air and gas supply pipes C' C² by branch pipes d .

The heat-retaining shell B² is supported at each end by a plate d^2 , and the shell B³ is similarly supported by plate d' , said plates 75 being slotted and fitting over studs d^3 , projecting from the frame-standards. The plates are also adjustable vertically by means of screws e and can be independently adjusted inwardly or outwardly through the medium 80 of screws $e' e^2$, respectively. By this inward adjustment of the end plates carrying the respective heat-retaining shells I am enabled to move the solder-bath receptacles toward and from each other, and thus adapt the distance 85 between the receptacles to the length of different cans. In this manner the soldering-machine may be utilized in connection with different-size cans.

Within bearings of the end standards E E' 90 of the machine work the cross-shafts E² E³, upon which are secured the chain-wheels F F'. Over these wheels work the endless-chain carrier F², by means of which the cans D² are carried through the machine. The endless 95 carrier is driven from cross-shaft E² by belt (not shown) working over belt-wheel E⁴, Fig. 3 of the drawings.

The cans to be soldered are fed to the primary heater at its feed end from a suitable 100 runway (not shown) and enter beneath the endless carrier F². This carrier conveys the

can over trough D', its top and bottom projecting beyond the sides of said trough. As carried over the trough D' the projecting ends are heated by the deflected heat from burners D³. As the can is carried beyond the primary heater it rolls onto the flux-holding troughs D, the heated ends riding upon the strip of absorbent material h, resting within the trough. By means of these strips of material the flux within the troughs is drawn upward. From the fluxing devices the cans are carried to the soldering, the top and bottom end resting within the slots a of the solder-receptacles, so as to be in contact with the molten solder therein. As carried the length of the receptacles the periphery of the top and bottom ends rotate within the solder-baths and the solder is thus applied to the joints. The soldered cans are discharged as carried beneath wheel F.

Each solder-bath receptacle is tapped by the solder-feed pipe G, through which solder is admitted to the receptacles in order to maintain the molten solder at an even level. The solder-bath receptacles B B' are slipped into the heat-retaining shells B² B³ from either end, each being open, and are held therein by the shoulders h' bearing upon the edges h² of the said shells. Preferably the feed-pipe G for the solder is only employed for the feeding of solder into the solder-bath in order to replenish the solder consumed by the soldering of the tops and bottoms onto the cans. The main supply of solder, or rather the solder-bath receptacles, are originally filled by removing the screw-plugs b' at one end and introducing stick solder therein until sufficient solder is introduced, which when melted will fill the said receptacles. The ends are then closed by screwing plugs b' therein. The square ends of these plugs are fitted through openings h³ of the slide-plates d' d². Inasmuch as the solder-bath receptacles are confined within heat-retaining shells and only a small portion of the molten solder is exposed through the slotted receptacles to the atmosphere, oxidation of the solder and loss by reason of oxidation is reduced to a minimum.

In order that the cans while carried through the machine may be held against end movement, the guide-rods K K' are provided. These rods are connected to brackets k, inwardly projecting from standards E E', and are located such a distance apart as to permit of the cans rolling freely between the same as carried through the primary heater, the flux-troughs, and solder-bath receptacles. These guide-rods prevent the cans shifting endwise while carried through the machine, and thus hold the same in proper alignment.

Having thus described the invention, what is claimed as new, and desired to be protected by Letters Patent, is—

1. In a machine of the character described, a pair of soldering-troughs arranged side by side, a pair of supporting members for each

trough, and means for adjusting either pair of said supporting members independently of the other pair to adjust one of the troughs independently of the other; substantially as 70 described.

2. In a machine of the character described, a pair of soldering-troughs arranged side by side, a pair of supporting-plates for the ends of each trough, the adjacent plates at the respective ends of the trough being arranged to slide the one upon the other, and means for adjusting each of said plates independently of the other plates; substantially as 75 described.

3. A tubular open-ended soldering-trough having a single narrow longitudinally-arranged slot a terminating at points intermediate of the ends of the trough, and a closure b' for the open end of the trough; substantially as 85 described.

4. A tubular soldering-trough having a single narrow longitudinally-arranged slot a terminating at points intermediate of the ends of the trough, a fill-opening at one end of the 90 trough, an auxiliary fill-opening in the body of the trough, and a feed-pipe G leading into said auxiliary fill-opening; substantially as described.

5. In a can-end-soldering machine, a heater 95 comprising a hollow trough upon which the cans to be operated upon are adapted to run and having sides inclined outwardly and upwardly, a plurality of burners disposed longitudinally of said trough and beneath the lower central portion thereof, said trough being of a width less than the length of the cans to permit the heating of both ends of said cans simultaneously, and a heat non-conducting filling in the trough and arranged to 100 underlie the central portion of the cans, substantially as described.

6. In a can-end-soldering machine, a heater comprising an elongated support for the cans to be operated upon and provided with upwardly and outwardly inclined sides and a flat upper surface upon which the cans are adapted to run, and a plurality of burners disposed longitudinally of said trough and beneath the lower central portion thereof, said 110 trough being of a width less than the length of the cans to permit the heating of both ends of said cans simultaneously, substantially as described.

7. In combination, a slotted tubular heater, 120 and a correspondingly-slotted soldering-trough seated in said heater and provided with lateral projections along its upper portion and engaging the edges of the tube surrounding the slot in the latter; substantially 125 as described.

8. In combination, a slotted tubular heater, a correspondingly-slotted soldering-trough, and means for supporting the soldering-trough in the heater comprising longitudinally-disposed shoulders h' at the upper portion of the sides of the former bearing upon 130

edges b^2 of the latter; substantially as described.

9. In combination, a slotted tubular heater, a correspondingly slotted soldering-trough seated in said heater and provided with lateral projections engaging the edges of the heater surrounding the slot in the latter, and a series of burners arranged longitudinally of the tubular heater beneath the same and pro-

jecting slightly thereinto through suitable 10 apertures formed in the bottom thereof, substantially as described.

In witness whereof I have hereunto set my hand.

HENRY C. BLACK.
